UNITED STATES PATENT OFFICE

142,608

DESIGN FOR A DRAWING INSTRUMENT

Florenz W. Ziegfeld, Chicago, Ill.

Application April 5, 1945, Serial No. 118,868

Term of patent 14 years

(Cl. D52—1)

To all whom it may concern:

Be it known that I, Florenz W. Ziegfeld, a citizen of the United States, residing at Chicago, in the county of Cook and State of Illinois, have invented a new, original, and ornamental Design for a Drawing Instrument, of which the following is a specification, reference being had to the accompanying drawing, forming a part thereof.

Referring to the drawing:

Fig. 1 is a plan view of a drawing instrument showing my new design;

Fig. 2 is an edge view thereof looking at one end thereof;

Fig. 3 is an edge view thereof looking at one side thereof, and

Fig. 4 is an enlarged detail vertical longitudinal section taken on the line 4—4 of Fig. 1.

I claim:

The ornamental design for a drawing instrument, as shown.

FLORENZ W. ZIEGFELD.
